**HOLDDOWN FOR ANCHORING WALL STUDS
IN FRAME CONSTRUCTION TO BUILDING
FOUNDATIONS**

Tyrell T. Gilb, Berkeley, Calif., assignor to
Simpson Company

Filed Oct. 30, 1970, Ser. No. 55,724

Term of patent 14 years

Int. Cl. D8—08

U.S. Cl. D8—233

FIG. 1 is a perspective view of a holddown for anchoring wall studs in frame construction to building foundations showing my new design.

FIG. 2 is a plan view thereof.

FIG. 3 is a side elevation view thereof.

FIG. 4 is a front elevation view thereof.

FIG. 5 is a perspective view of a modified holddown shown in FIGS. 1-4.

FIG. 6 is a plan view of the modified holddown.

FIG. 7 is a side elevation of the modified holddown.

FIG. 8 is a front elevation of the modified holddown.

The broken lines are shown for illustrative purposes only and form no part of the design.

I claim:

The ornamental design for a holddown for anchoring wall studs in frame construction to building foundations, substantially as shown and described.
